UNITED STATES PATENT OFFICE.

JAMES A. GREEN, OF BAY CITY, MICHIGAN, ASSIGNOR TO GREEN & STEVENS, OF SAME PLACE.

LUBRICATOR.

SPECIFICATION forming part of Letters Patent No. 288,328, dated November 13, 1883.

Application filed August 27, 1883. (No model.)

To all whom it may concern:

Be it known that I, JAMES A. GREEN, of Bay City, in the county of Bay and State of Michigan, have invented new and useful Improvements in Lubricators; and I do hereby declare that the following is a full, clear, and exact description thereof, reference being had to the accompanying drawings, which form a part of this specification.

10. This invention relates to certain new and useful improvements in lubricators wherein the valve which controls the outflow of the oil is actuated by the motion of the part to which it is attached.
15. The object of the invention is to produce a certainty of action in this class of lubricators and to control the opening of the valve to a greater or less degree, as more or less oil is required.
20. The invention consists in the peculiar construction, combination, and operation of the parts, as more fully hereinafter described.

In the accompanying drawings, which form a part of this specification, and in which my invention is shown in sectional elevation, A represents a chamber to receive the oil, through the bottom of which is a port for the discharge of the oil, such discharge being intermittent by the alternate opening and closing of the valve B, which is itself set immediately over the discharge-hole.

The upper end of the valve-stem is provided with a spring, C, the point of resistance of one end being a shoulder, *a*, or pin on the valve-stem, and at the other end against the adjacent wall of the chamber, and a set-screw, D, is provided, by means of which to regulate the throw of the valve.

A wrist-pin, E, rigidly secured between the walls of the box, has sleeved upon it a counter-balance, F, provided with a tongue, *b*, which engages with a slot or recess, *c*, in the adjoining face of the valve-stem. Set-screws H, projecting through each end of the chamber-walls, are employed to regulate the throw of this counter-balance in case it should be found necessary to relieve the strain that might otherwise come upon the wrist-pin, created by the sudden change of direction in the throw of such counter-balance.

The device being constructed as described,

and attached by the usual connections to a gang-saw mill and filled with oil, the sudden change at either end of the stroke of the saw has a tendency to send the oil to the opposite end of the chamber, and—for instance, if the mill is at the lower end of the stroke—the sudden change of the motion in the opposite direction will, by reason of the greater gravity of the counter-balance, cause the overhanging end of it to drop, thereby opening the valve and allowing an escape of oil, the flow of such oil being regulated by the distance to which the valve is set to open. As soon as the upward motion of the part to which the lubricator is attached overcomes the inertia, the spring upon the stem by its action closes the valve before the completion of the upward stroke, or nearly so, so that the reversal of the motion at the completion of such upward stroke will produce an actuation of the counter-balance directly contrary to that already described, so that in the down-stroke the valve will be closed. Although described as being attached to lubricate the slides of a gang-mill which stand vertical, it is evident that the same result would occur when attached to devices moving horizontally.

What I claim as my invention is—

1. A lubricator constructed substantially as described, and provided with a counter-balance which engages with the valve-stem, substantially as and for the purposes described.
2. A lubricator consisting of an oil-reservoir, the outflow of which is regulated by means of the intermittently-acting valve B, whose stroke is regulated by the set-screw D, substantially as specified.
3. A lubricator constructed substantially as described, wherein the radial throw of a pivoted counter-balance is regulated by means of the set-screw H, said counter-balance engaging with the valve-stem D, substantially as and for the purposes set forth.
4. A lubricator consisting of the oil-reservoir A, valve B, spring C, wrist-pin E, counter-balance F, and set-screws D H, the parts being constructed, arranged, and operating substantially as and for the purposes described.

JAMES A. GREEN.
